BUTTONHOLE SEWING MACHINE

Alfred R. Wood, Bridgeport, Conn., assignor to
The Singer Manufacturing Company, Elizabeth,
N. J., a corporation of New Jersey

Application July 15, 1944, Serial No. 545,035

16 Claims. (Cl. 112—73)

1

This invention relates to sewing machines and more particularly to sewing machines of the straight buttonhole type having mechanism whereby the length of the stitches is automatically increased at the opposite ends of the button-hole upon cessation of the feeding movements of the work-clamp for the purpose of producing barring stitches.

In the production of high grade buttonholes where the barring stitches are desired to be patterned in a neat, closely packed, stacked relation, it is imperative that the increase in the amplitude of the needle-vibration and the cessation of the feeding movements of the work-clamp at the beginning of the barring operation occur simultaneously. It is equally important that at the ending of the barring operation the amplitude of the needle-vibration decrease at the same time that the feeding movements of the work-clamp are resumed to form the other side stitches of the button-hole.

In previous machines of the type in which this invention is embodied, the mechanism employed for stopping the work-clamp when the barring stitches were started and for again starting the work-clamp when the needle-vibration was reduced to side-stitching length operated satisfactorily at slow speeds of stitch-formation. However, since the speed of operation of the sewing machine has now been increased as much as fifty per cent, the mechanism of the prior machines failed to perform its function with the requisite degree of accuracy and particularly at the end of the barring operation and at the time that the amplitude of needle-vibration was reduced and the feeding movements of the work-clamp resumed.

It is the primary object of the present invention to provide a mechanism by which the work-clamp shifting mechanism is instantly rendered ineffective or effective when the amplitude of vibration of the needle is increased to form the barring stitches or decreased to form the side stitches of the buttonhole.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 is a right side elevational view, partly

2

in section, of a buttonhole sewing machine embodying the invention.

Fig. 2 represents a horizontal sectional view taken along the line 2—2, Fig. 1.

Fig. 3 is a left side elevational view of the machine shown in Fig. 1.

Fig. 4 is a bottom plan view.

Fig. 5 represents an enlarged vertical sectional view taken substantially along line 5—5, Fig. 4.

10 Fig. 6 represents a vertical sectional view taken substantially along line 6—6, Fig. 4.

Fig. 7 is a top plan view of the bracket-arm of the machine.

15 Fig. 8 represents an enlarged vertical sectional view taken substantially along the line 8—8, Fig. 1, showing some of the details of the means employed for rendering the clutch effective or ineffective in rotating the feed-cam.

Fig. 9 represents an enlarged vertical sectional 20 view taken substantially along the line 9—9, Fig. 7.

Fig. 10 is an enlarged vertical sectional view taken substantially along the line 10—10, Fig. 3, showing the feed-shaft fitted with the spline having the clutch-releasing cone secured at its lower end and the annularly grooved collar secured at its upper end.

Fig. 11 represents a horizontal sectional view taken substantially along the line 11—11, Fig. 10.

30 Fig. 12 is an enlarged fragmentary top plan view of the needle-bar vibrating mechanism and the bar-stitch counting device, showing the relative position of the component parts thereof when the machine is producing the side-stitches of the buttonhole.

Fig. 13 is a fragmentary top plan view of the bar-stitch counting mechanism and shows the manner in which said mechanism is rendered ineffective during the production of the side-stitches 40 of the buttonhole.

Fig. 14 is a view similar to Fig. 12, but with the bar-stitch counting mechanism removed to show more distinctly the details of the needle-bar vibrating mechanism.

45 Fig. 15 is a view similar to Fig. 12, but with the needle-bar vibrating mechanism in position to produce the relatively long barring stitches and the bar-stitch counting device operating to determine the number of stitches comprising the 50 bar.

Fig. 16 represents an enlarged horizontal sectional view taken substantially along the line 16—16, Fig. 1.

Fig. 17 represents a view, partly in section, taken 55 along the line 17—17, Fig. 1, showing an adjust-

ment in the connections between the feed-cam and the work-clamp, whereby the machine can be set to sew various lengths buttonholes.

Fig. 18 represents an enlarged sectional view taken along the line 18—18, Fig. 10.

Fig. 19 represents an enlarged sectional view taken along the line 19—19, Fig. 11.

Fig. 20 represents a top plan view of the feed-cam.

Referring to the drawings, the machine chosen for the purposes of the present disclosure has a frame including a bed 1 from which rises a standard 2 of the bracket-arm 3 terminating in a head 4. Journaled in the bracket-arm 3 is a main-shaft 5 connected at its rearward end, by spur-gears, to a countershaft 6 driven by a belt adapted to run upon a nest of pulleys 7 carried by the countershaft 6, see Figs. 1 and 3. Journaled within the standard 2 is a vertical shaft 8 geared at its upper end to the main-shaft 5 and at its lower end to a bed- or hook-shaft 9 journaled in the bed 1. Secured at the outer end of the hook-shaft 9 is a rotary loop-taker or hook 10 adapted to cooperate with a thread-carrying needle 11 in the formation of lock-stitches. The needle 11 is carried by the lower end of a needle-bar 12 journaled for endwise reciprocatory movement in spaced bearings formed in a vibratory needle-bar-gate 13 supported upon pintles 14 within the head 4. The needle-bar 12 may derive its reciprocatory movements from the main-shaft 5 by means of any usual or suitable connections therewith.

The work to be buttonholed is adapted to be held in a work-clamp comprising the usual lower work-plate 15 and the upper clamp-foot 16, Fig. 1. The work-clamp is slowly moved in step-by-step fashion under the endwise reciprocatory and laterally vibratory needle 11, first away from the standard 2 and then towards the standard to cause the first and second rows of side zigzag stitches to be laid side by side in the work. The work-clamp derives its step-by-step movements from the usual feed-cam 17 carried on a vertically disposed feed-shaft 18 journaled in the bed 1 and bracket-arm 3 of the machine-frame. The connections between the work-clamp and the feed-cam are generally similar to the construction disclosed in the U. S. patent of E. B. Allen, No. 785,061, March 14, 1905. Referring to Figs. 4, 10, 17 and 20 it will be observed that-by-step movements of the work-clamp away from and back towards the standard 2 are obtained from a heart-shaped cam-groove 19 formed in the upper face of the feed-cam 17 through a bell-crank lever 20, the slotted limb of which is connected to the work-plate 15 by a link 21. To facilitate the proper adjustment of the connections between the feed-cam 17 and the work-clamp for the production of a predetermined length buttonhole, the link 21 adjacent the slotted limb of the bell-crank lever 20, Fig. 17, is formed with a pointer 22 which extends upwardly through a clearance slot 23 in the bed 1 of the machine and into register with a suitable indicator-plate 24 secured upon the bed 1. The indicia on the indicator-plate denote the various buttonhole sizes in button lignes. The connections employed for shifting the work-clamp sidewise so that the two rows of side stitches of the buttonhole may be properly spaced are similar to those in the above mentioned Allen patent and comprise a lever 25, Figs. 4 and 10, one end of which is connected to the work-plate 15 while the other

end tracks a suitable cam-groove 26 formed in the feed-cam 17.

The feed-cam 17 is secured to the feed-shaft 18 to rotate therewith and preferably by means of a collar 27, Figs. 5 and 10, brazed to the shaft 18 or fixed thereto by set-screws 28 and formed with a projection 29 provided with a dogging pin 30 adapted to enter a timing hole 31 formed in the feed-cam 17. The feed-cam 17 is held against the collar 27 with the dogging pin 30 in the timing hole 31 by a nut 32 threaded upon the feed-shaft 18. The above described means for securing the feed-cam to the feed-shaft is desirable for the reason that by removing the nut 32 the entire feed-cam 17 and its associated mechanism can be readily removed from the machine without having to withdraw the feed-shaft or disturb its timing.

The feed-cam 17 and the feed-shaft 18 are intermittently rotated by means of a one-way-acting clutch of the Horton type which is actuated by the vertical shaft 8. More specifically, the clutch preferably comprises an outer clutch drum 33 fixed, as clearly shown in Fig. 10, by a plurality of screws 34 to the recessed under surface of the feed-cam 17. Disposed within the clutch-drum 33 and freely rotatable upon the depending hub 35 (Fig. 10) of the feed-cam 17 is a live internal clutch-spider 36 formed preferably with three suitable cavities 37 provided with inclined hardened ware-plates 38. Disposed in each of the cavities 37 is a clutch-member 39 which is engaged by a plunger 40, Fig. 4, backed by a coil-spring 41, the plunger acting to bias the clutch-member 39 toward the narrow end of the cavity 37 and wedge the same between the inclined ware-plate 38 and the clutch-surface of the drum 33. The spider 36 is oscillated constantly about the axis of the feed-shaft 18 during the operation of the machine by means of an arcuate shaped actuating lever 42 secured at its inner end by screws 43 to the spider 36. At its other end the actuating lever 42 is connected by a link 44 to the outer end of a vertically disposed rock-shaft 46 (see Fig. 1) journaled in a bearing bushing 47 pressed into the machine bed 1. At its upper end the rock-shaft 46 has secured thereto a second rock-lever 48 connected to a pitman 49, Fig. 2; one end of said pitman embracing an eccentric 50 fast on the vertical shaft 8. As the shaft 8 is rotated, the eccentric 50 imparts to the rock-shaft 46 oscillatory movements which through the rock-lever 45, link 44 and actuating lever 42 oscillate the clutch-spider 36 about the axis of the feed-shaft 18. The clutch-spider 36, through the clutch-members 39, drives the clutch-drum 33 which rotates the feed-cam 17 and feed-shaft 18 intermittently in one direction. Retrograde motion of the feed-cam 17 is prevented by a common form of dog shown as 51 in Fig. 4.

The speed with which the feed-cam 17 is rotated is dependent upon the effective length of the actuating lever 42. The means employed in the machine chosen to illustrate the present invention for adjusting the effective length of the actuating lever is substantially the same as that forming the subject of the United States Patent No. 2,334,154 issued to A. R. Wood on November 9, 1943. As shown in Figs. 4 and 5, the actuating lever is formed with a longitudinal T-shaped slot 52 in which slides a block 53 provided with a depending ball-like member 54 embraced by the socketed end of the link 44. Threaded into a pro-

jection 55 on the block 53 is an adjusting rod 56 journaled against endwise movement in a bearing member 57 pivotally supported upon the clutch-spider 36. When it is desired to change the effective length of the actuating arm 42, the adjusting rod 56 is adapted to be turned by a suitable wrench in a manner fully disclosed in the above mentioned Wood patent. The turning of the adjusting rod 56 shifts the block 53 lengthwise of the actuating arm 42, thereby increasing or decreasing the oscillations imparted to the live clutch-spider, whereby the number of stitches forming the buttonhole can be readily controlled.

To prevent overthrow of the clutch during the high speed operation of the machine, the feed-cam 17 has embracing its grooved periphery for a major portion thereof a brake (Fig. 4) in the form of a wire loop 58 secured at one end preferably to a lug 59 cast integral with the machine bed 1. At its other end the wire loop 58 is hooked into one end of a coil-spring 60 connected at its other end to the free end of a member 61 adjustably fastened to an extension 62 fast on the rock-lever 45. As the rock-lever 45 is actuated to rotate the feed-cam 17 (see arrow in Fig. 4) the wire loop 58 through the coil-spring 60 is tightened about the periphery of the feed-cam 17 to such an extent that at the end of the stroke of the rock-lever 45, the wire loop is drawn sufficiently tight about the periphery of the feed-cam to brake the same and preclude any overthrow thereof. During the return stroke of the rock-lever 45, it will be understood that the tension applied to the wire loop 58 will be released. The particular form of brake above described forms the subject of my co-pending divisional application Serial No. 599,061, filed June 12, 1945. The principal advantage of this type of brake is that in initially engaging to turn the feed-shaft 18 the clutch does not have to overcome, in addition to the inertia of the parts, any appreciable braking force which may be needed at the end of the feed-cam advancing stroke to prevent overthrow of the feed-cam. In other words, with the improved wire-loop brake at the beginning of the feed-cam advancing stroke no braking action need be overcome, while, as the rock-lever 45 approaches the end of its advancing stroke, the braking action increases to a maximum so as to prevent overthrow. The gradual increase of the braking action as the end of the feed-advancing stroke is approached does not present any difficulty, inasmuch as the braking action is not applied to the feed-cam until after the clutch-members 39 are in wedging relation between the clutch-drum 33 and the spider 36. The fact that no braking action exists during the short period of time that the clutch-members 39 are moving into wedging relation minimizes clutch slippage.

As is common in many buttonhole sewing machines, the step-by-step movements of the work-clamp relative to the laterally vibratory needle are suspended for a short time at the opposite ends of the buttonhole, in order that a suitable number of barring stitches may be made at each end of the buttonhole. This suspension of the work-clamp feed is accomplished by automatically controlled means operable to disengage the clutch employed for intermittently turning the feed-shaft and then to permit engagement of the clutch after the production of a plurality of barring stitches, the exact number of which is determined by a suitable bar-stitch counting mechanism. To this end, the feed-shaft 18 is formed lengthwise thereof and preferably for its

entire length with a clearance opening or keyway 63 in which is disposed within the confines of the feed-shaft for free endwise movement a clutch-releasing rod or spline 64, Fig. 10. Secured to the lower end of the spline 64, preferably by screws 65, is a clutch-releasing sleeve 66 slidably mounted upon the feed-shaft 18. The clutch-releasing sleeve 66 adjacent its upper end is formed with a substantially cone-shaped cam-surface 67 which, when the sleeve is elevated to clutch-releasing position, is adapted to engage the respective tail portion of each of a plurality of clutch-element-releasing levers 68 journaled upon pivot-studs 69 depending from the spider plate 36, causing the clutch-element-releasing levers to engage the clutch-members 39 and displace them to a position such that wedging of the clutch-members between the spider 36 and the clutch-drum 33 cannot take place. Obviously, when the clutch-members 39 are thus maintained in non-wedging position, actuation of the spider 36 is ineffective to turn the feed-cam 17. During the time the feed-cam remains stationary there is no relative feed between the work-clamp and the laterally vibratory needle 11 and hence continued vibration of the needle effects the production of barring stitches arranged in a neat stacked relation. To maintain the components of the entire clutch assembly in proper co-operating relationship a plurality of retainers 70 are provided (Figs. 4 and 5), which retainers are fastened by screws 71 to the live clutch-spider 36. Each of these retainers is formed at its inner end in a manner to project beneath one of the clutch-element-releasing levers 68 thereby to hold the lever upon its respective pivot-stud 69, while the body portion of each retainer underlies the clutch-member 39 to maintain the latter in its cavity 37. The other end of each of the retainers 70 is bent upwardly into substantially hook-shape about a horizontal flange 72 integral with the clutch-drum 33. By virtue of the above described retainers 70, the clutch-members 39 and the clutch-element-releasing levers 68 are held in proper assembled position, and the live clutch-spider is maintained within the clutch-drum 33. Removal of the clutch-releasing sleeve 66 and the retainers 70 readily permits complete disassembling of the clutch mechanism.

The means by which the spline 64 is shifted up and down in its keyway 63 to elevate or lower the clutch-releasing sleeve 66 comprises a collar 73 slidably mounted upon the feed-shaft 18 and secured preferably by screws 74 to the spline 64. Formed in the collar 73 is an annular recess 75 (Figs. 8 and 16) entered by a roller 76 carried on the inner end of a lifting lever 77 freely pivoted on a fulcrum-stud 78 journaled in spaced bearing lugs 79 integral with the wall of the bracket-arm 3. The lifting lever 77 is adapted to be actuated in a counterclockwise direction, Fig. 10, to raise the spline 64 and consequently the clutch-releasing sleeve 66 to render the clutch ineffective, by a vertically disposed rocker 80 secured on the fulcrum-stud 78, preferably as shown in Fig. 16, by a set-screw 81 and a taper-pin 82. The lower end of the rocker 80 is in peripheral contact with a feed-cam release actuating element in the form of a two-lobe cam 83, Fig. 11, which is fast upon the feed-shaft 18. Each lobe of the cam is cut with a gradual rise 84 terminating in a drop-off 85 so that, as the feed-shaft 18 is turned, the lower end of the rocker 80 is gradually swung outwardly in opposition to a coil-spring 86, which is anchored at one end

to an arm 87 on the bracket-arm 3 and connected at its other end to the lower end of a lever-arm 88 pinned to the fulcrum-stud 78. As the outwardly swinging motion of the rocker 80 is continued, a pawl-lever 89 (Figs. 8 and 10) pivotally carried on the rocker 80 is raised relative to the lifting lever 77 until a step or shoulder 90 formed on the pawl-lever 89 moves above the level of the upper edge of the lifting lever 77 when, under the action of the spring 91, the pawl-lever 89 snaps into a substantially vertical position connecting the lifting lever 77 with the rocker 80, see full line position in Fig. 18. As the feed-shaft 18 continues to turn and the drop-off of the cam 83 passes by the lower end of the rocker 80, the rocker snaps inwardly under the influence of the coil-spring 86 and into a position determined by an adjustable stop 92 carried by the rocker 80. This rapid inward motion of the rocker 80, through the pawl-lever 89 and the lifting lever 77 raises the clutch-releasing sleeve sufficiently to force the clutch-elements 39 into an ineffective or declutching position. In order to insure the rapid shifting of the clutch-elements 39 into declutching position, the rise on the cam-lobes 84 preceding the drop-offs 85 is of such height that the shoulder 90 on the pawl-lever 89 is raised to the extent that clearance exists between the shoulder 90 and the upper edge of the lifting lever 77 (Figs. 10 and 18). This clearance permits the pawl-lever 89 to strike the lifting lever 77 with some force when the rocker 80 snaps inwardly under the influence of the coil-spring 86, the sharp blow of the pawl-lever on the lifting lever acting to drive the clutch-elements 39 out of wedging relation. When the clutch-elements are in their ineffective position, the feed-shaft is not intermittently rotated with the continued operation of the live clutch spider 36, but remains stationary. Thus the work-clamp is not shifted relatively to the laterally vibratory needle. As will be observed in Figs. 11 and 19, the two-lobe cam 83 is preferably constructed so that its two drop-offs 85 are capable of adjustment relative to the main body of the cam to effect an exact adjustment of the timing of the drop-offs relative to the rocker 80. To this end, the main body of each of the lobes 84 is provided with an arcuate recess 93 in which is received a secondary cam-section 94 adapted to be clamped in proper adjusted position by a clamp-screw 95 extending through an elongated aperture 96 in the main body of the cam and threaded into the secondary cam-section 94. The timing adjustment provided by the secondary cam-sections 94 insures that the feed-cam 17 is rotated to a position such that the roller on the end of the work-plate side-shifting lever 25 is disposed in the section 26^a or 26^b of the cam groove 26 formed in the feed-cam 17 before the drop-off 85 passes by the rocker 80. In other words, by properly adjusting the secondary cam-sections 94 the needle is unerringly shifted to a position central of the buttonhole prior to the automatic increase in the amplitude of the needle vibrations preparatory to the production of the barring stitches.

To effect the production of the barring stitches during the time that the work-clamp is stationary, the amplitude of the lateral vibrations of the needle is customarily increased preferably to substantially twice that of the lateral vibrations of the needle during the formation of the side stitches. The means by which this is accomplished in the machine illustrated is substantially the same as that disclosed in the U. S. patent of

E. B. Allen, No. 784,291, dated March 7, 1905, but differing therefrom in details adapting the mechanism for more accurate operation at higher speeds. As hereinbefore described, the needle-bar-gate 13 is supported for vibratory movements on the pintles 14, Fig. 1. Connected to the upper end of the needle-bar-gate 13 is one end of an endwise extensible link 97 adjustably connected at its other end to a vibratory lever 98 fulcrumed on a pivot-stud 99 threaded into the bracket-arm 3. The vibratory lever 98 is adapted to be actuated by a connector-link 100 operatively connected, in a manner later to be described, to the inner end of an oscillatory actuator-lever 101 (Figs. 8, 9 and 14) fulcrumed upon a stud 102 threaded into the bracket-arm 3. The other end of the actuator-lever 101 has fixed to it a roller 103 which tracks a cam-groove 104 formed in a cam 105 fast upon the countershaft 6, the speed of rotation of which is one-half that of the arm-shaft 5 during the normal button-holing cycle. It will be understood from the above description that rotation of the cam 105 will cause the actuator-lever 101 to oscillate about its fulcrum-stud 102, thus transmitting vibratory movements to the needle-bar-gate 13 through the connector-link 100, vibratory lever 98 and link 97. Adjustment of the length of the link 97 provides for properly centralizing the stitches relative to the usual buttonhole slit. Adjustment of the end of the link 97 on the vibratory-lever 98 permits regulation of the amplitude of vibration of the needle-bar-gate 13 and hence the length of the stitches forming the buttonhole.

It will be understood that the oscillatory actuator-lever 101 and the connector-link 100 can be connected together in two positions; one of which is the side-stitching position and is close to the fulcrum axis of the actuator-lever 101 and the other of which is the bar-stitching position and is remote from the fulcrum axis of the actuator-lever. Considering first the side-stitching position, it will be observed from Fig. 14 that the connector-link 100 is formed with a notch 106 shaped with a flaring mouth and a narrow throat, the latter of which is sized to snugly engage the periphery of an upstanding pin 107 attached to the actuator-lever 101. The connector-link 100 is biased by a coil-spring 108 in a direction such that the throat of the notch 106 is maintained in engagement with the pin 107. Through the medium of the pin 107 and notch 106 the connector-link 100 is reciprocated endwise by the oscillatory actuator-lever 101 and thereby imparts movement to the needle-bar-gate 13.

Considering now the bar-stitching position, it will be seen in Figs. 8 and 14 that the connector-link 100 has depending from it a roller 109 which extends into a keyhole slot 110 formed in the actuator-lever 101 at a distance more remote from the fulcrum axis of the actuator-lever 101 than the pin 107. The proportions of the keyhole slot 110 are such that when the roller 109 is disposed within the larger end of the slot, as shown in Fig. 14, the clearance between the sides of the slot 110 and the roller 109 is such as not to interfere with the operation of the connector-link 100 by the actuator-lever 101. However, when the roller 109 is shifted into the narrow portion of the keyhole slot 110 for production of the barring stitches (see Fig. 15), the roller 109 engages the sides of the slot 110 and thereby connects the link 100 with the oscillatory actuator-lever 101. When thus connected, the pin 107 projecting upwardly from the actuator-lever 101

is located in the widely flaring mouth of the notch 106. From the above description it will be understood that when the connector-link 100 is connected to the oscillatory actuator-lever 101 by means of the notch 106 and the pin 107 (Fig. 14) the needle-bar-gate is vibrated to effect the production of side-stitches, and that when the connector-link 100 and the oscillatory actuator-lever 101 are connected together by the roller 109 and the keyhole slot 110 (Fig. 16) the needle-bar-gate is vibrated to effect the production of the longer barring stitches. The position of the roller 109 in the narrow portion of the keyhole slot 110 is determined by the adjustable stop screw 92 threaded into the rocker 80.

The means for shifting the connector-link 100 from side-stitching position (Fig. 14) to the bar-stitching position (Fig. 15) is automatic in its action and will now be described. As the lower end of the rocker 80 is gradually swung outwardly in opposition to the coil-spring 86 (Fig. 10) by the cam 83 on the feed-shaft 18, the upper end of the rocker 80 moves inwardly and carries with it a pawl 111 secured to the rocker by a ball-stud 112. The pawl 111 at its inner end is forked to provide two limbs 113 and 114 of which limb 113 is formed with a shoulder 115 adapted to snap, under the influence of a coil-spring 116, about a projection 117 secured on the connector-link 100 when the pawl 111 moves inwardly as a result of the movement of the rocker 80 in response to the turning of the cam 83. Thus it will be seen that the upper end of the rocker 80 is connected to the connector-link 100 when the oscillatory actuator-lever 101 and the connector-link are operating in their side-stitching position. When the cam 83 on the feed-shaft 18 is rotated to the point where one of its drop-offs 85 passes by the lower end of the rocker 80 the rocker, as previously explained, snaps into a substantially vertical position under the influence of the coil-spring 86 which is stronger than coil-spring 108 and thereby simultaneously raises the clutch-releasing sleeve 66 to render the feed-clutch ineffective and shifts the connector-link 100 from its side-stitching position into its bar-stitching position. In other words the rocker 80, when it snaps into a substantially vertical position, acts through the pawl-lever 89, lifting lever 71, spline 64 and clutch-releasing sleeve 66, to render the feed-clutch ineffective, thus terminating the step-by-step movements of the work-clamp and simultaneously shifting the connector-link 100 from the side-stitching position to the bar-stitching position. In order to relieve the needle-thread of some of its tension during the formation of the barring stitches, the thread-disks of the usual tension device 118 are adapted to be separated by a disk-separating plunger 119 (Fig. 1) which is moved upwardly by a cam 120, attached to the connector-link 100, when the connector-link is in its bar-stitching position.

The number of stitches included in each bar is determined by a suitable bar-stitch counting mechanism similar in design to that disclosed in the U. S. Patent No. 806,231 issued to E. B. Allen, December 5, 1905. Referring particularly to Figs. 9, 12, 13, 14 and 15, there is mounted for limited turning movement on the upper end of the fulcrum-stud 102 a ratchet-wheel 121 secured in position by a screw 122 (Fig. 9) threaded into the stud 102. Interposed between the head of the screw 122 and the top of the fulcrum-stud 102 is a disk 123 resting upon a coiled spring 124 which functions to bias the ratchet-wheel 121

in a clockwise direction, as seen in Fig. 13, against an adjustable stop 125 depending from a cover-plate 126 and adapted to be clamped in desired set position by a thumb-nut 127. To facilitate the proper setting of the stop 125 to obtain the desired number of stitches in the bar there is provided a pointer 128 (Fig. 7) cooperating with suitable indicia scribed on the cover-plate 126. As will be seen in Fig. 13, that portion of the ratchet-wheel 121 which is normally biased into contact with the adjustable stop 125 comprises an arcuate plate-member 129 clamped for limited circular adjustment by screws 130 in an annular recess 131 formed in the upper face of the ratchet-wheel 121. The arcuate plate-member 129 is adjustably clamped upon the ratchet-wheel 121 so that different teeth on the periphery of the ratchet-wheel may be brought into use, whereby the life of the ratchet-wheel is increased.

The ratchet-wheel 121 is adapted to be advanced in a counterclockwise direction as viewed in Fig. 16 by an actuating pawl 132 pivotally mounted on an extension 133 of the oscillatory actuator-lever 101; the actuating pawl being biased into engagement with the teeth in the ratchet-wheel 121 by a leaf spring 134. Cooperating with the actuating pawl 132 in advancing the ratchet-wheel 121 is a detent-pawl 135 which functions to prevent retrograde turning of the ratchet-wheel. It will be understood that as the actuator-lever 101 is oscillated about its fulcrum-stud 102 by the cam 105 the actuating pawl 132 is operated in such a manner as to engage and advance the ratchet-wheel 121 tooth-by-tooth and that the detent-pawl 135 maintains the ratchet-wheel in its various steps of advancement. After the number of barring stitches to which the pointer 128 is set has been produced, during which time the ratchet-wheel 121 is being advanced by the actuating pawl 132, a trip-plate 136 adjustably secured in the annular recess 131 formed in the ratchet-wheel 121 is brought into engagement with a pin 137 depending from a cross-lever 138 pivoted intermediate its ends on a stud 139 threaded into the cover-plate 126, Fig. 15. After engagement of the pin 137 by the trip-plate 136, further turning of the ratchet-wheel 121, under the action of the actuating pawl 132, swings the cross-lever 138 about its pivot 139 in the direction indicated by the arrow in Fig. 15 thus moving its free end into contact with the upstanding tail portion of the pawl-lever 89. Continued swinging movement of the cross-lever 138 turns the pawl-lever 89, against the action of the spring 91, thereby moving its shoulder 90 from its position vertically above the lifting lever 71 to the position indicated in dotted lines in Fig. 18. Depending from the cross-lever 138 is a release-pin 140 which, after the pawl-lever 89 is swung out of operative relation with the lifting lever 71, is adapted to move into contact with the limb 114 of the pawl 111, Fig. 15. Further turning of the cross-lever 138 in response to the step-by-step advance of the ratchet-wheel 121 swings the pawl 111 about its ball-stud 112 causing the limb 113 of the pawl 111 to release the projection 117 on the connector-link 110. When the projection 117 is released the connector-link 110, under the influence of the coil-spring 108, snaps from barring position, Fig. 15, to side-stitching position, Fig. 12. In moving from barring position to side-stitching position a projection 141 on the connector-link 100 engages a tail-member 142 on the ratchet-wheel actuating pawl 132 and shifts the actuating pawl in opposition to the leaf-spring

134, from its effective position shown in Fig. 15 to its ineffective position shown in Figs. 12 and 13. As shown in Fig. 13 this shifting of the actuating pawl 132 causes it to move into engagement with the detent-pawl 135 and to move the latter against its spring 143 out of engagement with the teeth on the ratchet-wheel 121. When the ratchet-wheel is thus released from the detent pawl the spring 124 biases the ratchet-wheel 121 in a clockwise direction, Fig. 13, and against the stop 125, whereby the bar-stitch counting mechanism is reset for the subsequent barring operation.

In order to resume the side-stitching operation at the completion of the barring operation, it is required that the clutch-releasing sleeve 66 be depressed to permit the clutch-members 39 to assume their wedging relation between the clutch-drum 33 and the live clutch spider 36. To this end, the connector-link 100 at its free end extends laterally and then forwardly to terminate in a relatively short arm 144 fitted with an adjustable screw 145. As shown in Fig. 15 when the connector-link 100 is located in its barring position the adjustable screw 145 is spaced from the vertical limb 146 of a bell-crank lever 147 freely pivoted upon the fulcrum-stud 78, Fig. 16. When the connector-link 100 is released from the pawl 111 at the completion of the barring operation and snaps from its barring position (Fig. 15) into its side-stitching position (Fig. 12), the screw 145 strikes the vertical limb 146 of the bell-crank lever 147, rapidly turning it about the fulcrum-stud 78. As the bell-crank lever turns, the horizontal limb 148 thereof moves downwardly and a roller 149 carried at the free end of the horizontal limb 148 and disposed in the annular recess 75 of the collar 73 slides the collar downwardly on the feed-shaft 18. The collar through the spline 64 lowers the clutch-releasing sleeve 66 to a position such that the clutch-element-releasing levers 68 do not prevent the clutch-members 39 from wedging the live clutch-spider 36 to the clutch-drum 33.

From the above description it will be understood that the present invention contemplates a mechanism whereby the suspension of the work-clamp feed is accomplished with certainty, by automatically controlled means operable to disengage the clutch employed for intermittently turning the feed-shaft and which will permit the unerring engagement of the clutch to reestablish the work-clamp feed after the production of a plurality of barring stitches, the number of which is determined by a suitable bar-stitch counting mechanism.

Having thus set forth the nature of the invention, what I claim herein is:

1. In a buttonhole sewing machine, in combination, stitch-forming mechanism including an endwise reciprocatory and laterally vibratory needle, a work-holder, a rotary shaft, a feed-cam carried by said shaft, operative connections with said feed-cam for relatively shifting said stitch-forming mechanism and work-holder to sew about a buttonhole, clutch means for rotating said shaft, and means including an actuating member shiftable axially of said shaft for disabling said clutch means during the formation of the buttonhole.

2. In a buttonhole sewing machine, in combination, stitch-forming mechanism including an endwise reciprocatory and laterally vibratory needle, a work-holder, a rotary shaft, a feed-cam carried by said shaft, operative connections with

said feed-cam for relatively shifting said stitch-forming mechanism and work-holder to sew about a buttonhole, clutch means for rotating said shaft, and means including an actuating member shiftable axially of and rotatable with said shaft for disabling said clutch means during the formation of the buttonhole.

3. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, and means for relatively moving the stitch-forming mechanism and work-holder to sew about a buttonhole, said means including a shaft, a feed-cam mounted on said shaft, and a clutch for turning said feed-cam, and means including a member extending lengthwise of said shaft and actuated by said barring mechanism for rendering said clutch ineffective to rotate said shaft.

4. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, means for relatively moving the stitch-forming mechanism and work-holder to sew about a buttonhole, said means including a shaft having a clearance opening extending lengthwise thereof, a feed-cam mounted on said shaft, and a clutch for turning said feed-cam, and a clutch-releasing rod slidable in the clearance opening in said shaft for rendering said clutch ineffective, thereby to interrupt the relative movement between said stitch-forming mechanism and said work-holder upon initiation of the barring operation.

5. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, and means for relatively moving the stitch-forming mechanism and work-holder to sew about a buttonhole, said means including a shaft arranged so that said barring mechanism is disposed adjacent one end of the shaft, a feed-cam mounted on said shaft adjacent the end remote from the barring mechanism, a clutch for turning said shaft; and a clutch-releasing rod extending lengthwise of said shaft and actuated by said barring mechanism for rendering said clutch ineffective, thereby to interrupt the relative movement between said stitch-forming mechanism and said work-holder.

6. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, and means for relatively moving the stitch-forming mechanism and work-holder to sew about a buttonhole, said means including a shaft having a clearance opening formed lengthwise thereof, a feed-cam mounted on said shaft, an actuating clutch coaxial with said shaft and operated to turn said feed-cam, and a clutch-releasing rod disposed in said clearance opening and shiftable lengthwise of said shaft under the

influence of said barring mechanism to render said clutch ineffective to turn said feed-cam.

7. A buttonhole sewing machine having, in combination, a work-holder, stitch-forming mechanism including a reciprocatory and laterally vibratory needle and barring mechanism for changing the amplitude of vibration of the needle to sew barring stitches at an end of the button-hole, and means for relatively moving the stitch-forming mechanism and work-holder to sew about a buttonhole, said means including a shaft having a clearance opening formed lengthwise thereof, a feed-cam mounted on said shaft, a clutch mounted to turn said shaft, said clutch including a drum, a spider, and at least one clutch-member disposed between said drum and said spider, a rod disposed in said clearance opening and shiftable lengthwise of said shaft under the influence of said barring mechanism, and an element secured to said rod and positioned to cause said clutch-member to be retracted from effective action when said rod is shifted, thereby to render said clutch ineffective to turn said shaft.

8. A buttonhole sewing machine having, in combination, a work-holder, stitch-forming mechanism including a reciprocatory and laterally vibratory needle and barring mechanism for increasing the amplitude of vibration of the needle to sew barring stitches at an end of the buttonhole, and means for relatively moving the stitch-forming mechanism and work-holder to sew about a buttonhole, said means including a shaft, a feed-cam mounted on said shaft, a clutch mounted to turn said shaft, a member extending lengthwise of said shaft and having an inoperative position in which said clutch is effective and an operative position in which said clutch is ineffective, a feed-cam release actuating element fast on said shaft, means connecting said feed-cam release actuating element to said member for shifting said member into its operative position, and means actuated by said barring mechanism for shifting said member into its inoperative position.

9. A buttonhole sewing machine having, in combination, a work-holder, stitch-forming mechanism including a reciprocatory and laterally vibratory needle and barring mechanism for changing the amplitude of vibration of the needle to sew barring stitches at an end of the button-hole, said means including a shaft, a feed-cam mounted on said shaft, a clutch mounted to turn said shaft, a member extending lengthwise of said shaft and having an inoperative position in which said clutch is effective and an operative position in which said clutch is ineffective, a feed-cam release actuating element fast on said shaft, means connecting said feed-cam release actuating element to said member for shifting said member into its operative position, means actuated by said barring mechanism for shifting said member into its inoperative position, and means for varying the timing between said feed-cam and said feed-cam release actuating element.

10. A buttonhole sewing machine having, in combination, a work-holder, stitch-forming mechanism including a reciprocatory and laterally vibratory needle and barring mechanism for changing the amplitude of vibration of the needle to sew barring stitches at an end of the button-hole, and means for relatively moving the stitch-

forming mechanism and work-holder to sew about a buttonhole, said means including a shaft, a feed-cam mounted on said shaft, a clutch mounted to turn said shaft, a member extending lengthwise of said shaft and having an inoperative position in which said clutch is effective and an operative position in which said clutch is ineffective, a feed-cam release actuating element fast on said shaft, means connecting said feed-cam release actuating element to said member for shifting said member into its operative position, and means actuated by said barring mechanism for shifting said member into its inoperative position, said feed-cam release actuating element being adjustable to vary the timing between the feed-cam and the feed-cam release actuating element.

11. A buttonhole sewing machine having, in combination, a work-holder, stitch-forming mechanism including a reciprocatory and laterally vibrating needle and barring mechanism for changing the amplitude of vibration of the needle to sew barring stitches at an end of the buttonhole, and means for relatively moving the stitch-forming mechanism and work-holder to sew about a buttonhole, said means including a shaft arranged so that said barring mechanism is disposed adjacent one end of the shaft, a feed-cam mounted on said shaft remote from said barring mechanism, a clutch located adjacent said feed-cam and mounted to turn said shaft, a member extending lengthwise of said shaft and having an inoperative position in which said clutch is effective and an operative position in which said clutch is ineffective, a feed-cam release actuating element fast on said shaft intermediate said feed-cam and said barring mechanism, means connecting said feed-cam release actuating element to said member for shifting said member into its operative position, and means actuated by said barring mechanism for shifting said member into its inoperative position.

12. A buttonhole sewing machine having, in combination, a work-holder, stitch-forming mechanism including a reciprocatory and laterally vibratory needle and barring mechanism for changing the amplitude of vibration of the needle to sew barring stitches at an end of a button-hole, and means for relatively moving the stitch-forming mechanism and work-holder to sew about a buttonhole, said means including a shaft, a feed-cam mounted on said shaft, a clutch for turning said shaft, said clutch having a driven element and a constantly operating driving live element, and means interconnected with said barring mechanism for rendering said live element ineffective during the continued operation of the live element of said clutch, thereby to interrupt the relative movement between said stitch-forming mechanism and said work-holder to form barring stitches.

13. A buttonhole sewing machine having, in combination, a frame including a bed and an overhanging bracket-arm, an actuating shaft journaled in said frame, a work-holder, stitch-forming mechanism including a reciprocatory and laterally vibratory needle, and means for relatively moving the stitch-forming mechanism and work-holder to sew about a buttonhole, said means including a feed-cam, a clutch for turning said feed-cam, a clutch actuating arm, a rock-shaft journaled in said frame in substantial parallelism with said actuating shaft, a plurality of rock-levers connected to said rock-shaft, a link connecting one of said rock-levers to said clutch-

15

actuating arm, an eccentric fast on said actuating shaft, and a pitman connecting another of said rock-levers to said eccentric.

14. A buttonhole sewing machine having, in combination, a frame including a bed and an overhanging bracket-arm, an actuating shaft vertically disposed and journaled in said frame, a work-holder, stitch-forming mechanism including a reciprocatory and laterally vibratory needle, and means for relatively moving the needle, and means for relatively moving the stitch-forming mechanism and work-holder to sew about a buttonhole, said means including a feed-cam, a clutch disposed within said bed for turning said feed-cam, a clutch actuating arm, a rock-shaft journaled in said bed in substantial parallelism with said actuating shaft, a plurality of rock-levers carried by said rock-shaft, a link connecting one of said rock-levers to said clutch-actuating arm, an eccentric fast on said actuating shaft, and a pitman connecting another of said rock-levers to said eccentric.

15. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, means for relatively moving the stitch-forming mechanism and work-holder to sew about a buttonhole, said means including a shaft, a feed-cam mounted on said shaft, a clutch mounted to turn said shaft, a member extending lengthwise of said shaft and having an inoperative position in which said clutch is effective and an operative position in which said clutch is ineffective, a feed-cam release actuating

ing element fast on said shaft, means connecting said feed-cam release actuating element to said member for shifting said member into its operative position, said last named means including a lifting lever operatively connected with said member, a rocker actuated by said feed-cam release actuating element, and a pawl-lever adapted to connect said rocker with said lifting lever, and means actuated by said barring mechanism for shifting said member into its inoperative position.

16. A buttonhole sewing machine having, in combination, a work-holder, stitch-forming mechanism including a reciprocatory and laterally vibratory needle and barring mechanism for changing the amplitude of vibration of the needle to sew barring stitches at an end of the buttonhole, and means for relatively moving the stitch-forming mechanism and work-holder to sew about a buttonhole, said means including a shaft, a feed-cam mounted on said shaft, a clutch mounted to turn said shaft, a member extending lengthwise of said shaft and having an inoperative position in which said clutch is effective and an operative position in which said clutch is ineffective, a feed-cam release actuating element fast on said shaft, means connecting said feed-cam release actuating element to said member for shifting said member into its operative position, and means for shifting said member into its inoperative position, said last named means including a lever actuated by said barring mechanism and operatively connected to said member.

ALFRED R. WOOD.
